UNITED STATES PATENT OFFICE.

JOSEPH M. VANOVER, OF TERRE HAUTE, INDIANA, ASSIGNOR OF THREE-FOURTHS TO WARREN W. FERIS, JAMES Y. WRIGHT, AND H. E. HENRY, ALL OF SAME PLACE.

WIRE FENCE.

SPECIFICATION forming part of Letters Patent No. 362,911, dated May 10, 1887.

Application filed January 15, 1887. Serial No. 234,451. (No model.)

To all whom it may concern:

Be it known that I, JOSEPH M. VANOVER, a citizen of the United States, residing at Terre Haute, in the county of Vigo and State of Indiana, have invented certain new and useful Improvements in Wire Fences; and I do hereby declare the following to be a full, clear, and exact description of the invention, such as will enable others skilled in the art to which it appertains to make and use the same.

This invention relates to certain new and useful improvements in wire fences; and it consists, substantially, in the same as constructed, and in such peculiar arrangement, construction, and combinations of parts, as will hereinafter be more particularly described, and pointed out in the claims.

The object of the invention is to simplify the construction of fences of this character, and to thereby economize in cost over many former inventions heretofore devised, and to render the erection thereof so easy as to require but little or no skill for the performance thereof.

Further, the invention has for its object to provide automatic tightening devices at the end of each fence-section, by which a self-conformity to expansion of the wires is had resultant from thermal changes and conditions of the atmosphere, and also to contractions of the wires due to the fall or lowering of the temperature.

Finally, the invention has additional objects in view, all as will more fully appear from the description hereinafter following, when taken in connection with the accompanying drawings, wherein—

Figure 1 represents a vertical longitudinal elevation of a section of fence wherein my improvements are embodied. Fig. 2 represents a perspective view of fence-post employed in the practice of my invention, the same indicating more clearly the construction thereof. Fig. 3 is a view in detail, showing the automatic tension or tightening mechanism employed at one end of each fence-section.

Reference being had to the several parts by the letters marked thereon, A and B each represent a post or upright arranged at opposite ends of a fence-section, and which are prefer-

ably each provided with a base, *a*, which are 50 inserted in the ground for the purpose of maintaining these posts in a permanent upright position. Extending through suitable openings in the post marked A, and likewise through two movable upright rods, C and D, are screw 55 rods or bolts E E, preferably three in number. These screw-bolts have arranged upon them between the rods C D spiral springs F, the same having their bearing between the said upright rods. The screw rods or bolts on which 60 these springs are held are headed on one end, while their opposite extremities are screw-threaded, and are provided with adjusting-nuts *e* to the outer side of the vertical upright 65 or post A.

It is evident that by screwing up the nuts *e* the tension of the springs will be increased, and thereby tend to force the inner rod, C, outwardly, and thus exert a tension or strain upon the longitudinal wires H, secured to this rod 70 at one end and secured to the post B at the opposite end of the fence section, the said wires being attached or secured in any suitable or preferred manner.

At suitable intervals of the fence section I 75 employ the metallic fence-posts L, which are corrugated longitudinally or lengthwise for the purpose of obtaining maximum strength, or, in other words, they are of an approximate S shape in horizontal section. These 80 posts are also provided with suitable supporting-bases, *g*, which may be either seated upon the surface of or inserted in the ground. At alternate points of their length and near the edges thereof they are formed or provided with 85 holes or perforations *i*, through which the wires H pass, and from which it will be seen that, in addition to the wires being supported by the posts, they themselves serve to support the posts from opposite sides. For the purpose 90 of facilitating ready insertion of the wires in the openings, I provide slits *k k'*, and it will thus be seen that by bending the slight wing or severed portion produced by these slits or incisions the said wires may be quickly inserted and the metal afterward bent back into place to prevent the wires from becoming unseated or dislodged. In the top edges of these 95

corrugated posts I provide suitable notches, *l*, which are for the reception of top rails of wood or other suitable material.

Intermediate of the corrugated metallic posts and the end uprights or posts, *A* and *B*, I employ auxiliary wire posts or stays *M*, constructed of two or more wires woven or twisted into the longitudinal wires of the fence, as shown, and which are for the additional purpose of strength and guides. They are, in like manner as the rest, preferably provided with supporting-bases, as indicated by the letter *m*.

From the foregoing description it is thought that the construction, arrangement, and operation of the parts contributing toward my invention will be fully understood; but it may be stated that in erecting a fence according to my invention, after the longitudinal wires have been properly located in position and fastened at their extremities in the manner shown, the automatic compensator is adjusted to draw the wires taut, and it has been found that when this is done the tension of the springs is usually sufficient to automatically take up any slack in the wires produced by thermal changes, and it is of course apparent that a reversal of this action will take place on contraction of the wires resultant from extreme cold or lowering of the atmospheric temperature. If, however, it should be found after once setting the tension devices that they insufficiently perform the function of tighten-

ing the wires, it is only necessary to tighten the nuts on the screw-bolts until the proper adjustment is attained.

Having thus described my invention, what I claim as new, and desire to secure by Letters Patent, is—

1. In a wire fence, the combination of the end posts, *A* and *B*, the movable upright rods *C* and *D*, the screw-bolts passing through these rods and post *A*, and having adjusting-nuts, springs borne on these bolts between the rods, the corrugated posts *L*, having alternating openings on their opposite edges, and slit, as at *k k'*, the wires *H*, passing through said openings and secured to the rod *C* and post *B*, and auxiliary posts or stays constructed of two or more wires woven or twisted into the wires *H*, substantially as described.

2. In a wire fence, the combination of the end posts, *A* and *B*, the movable upright rods *C* and *D*, the screw-bolts passing through these rods and post *A*, and having adjusting-nuts, springs borne on these bolts between the rods, and the wires *H*, secured to the rod *C* and end post, *B*, all substantially as shown, and for the purpose described.

In testimony whereof I affix my signature in presence of two witnesses.

JOSEPH M. VANOVER.
